UNITED STATES PATENT OFFICE

2,189,740

VENDING MACHINE

Bert E. Mills, Oak Park, Ill., assignor to Mills Novelty Company, Chicago, Ill., a corporation of Illinois

Application December 27, 1935, Serial No. 56,367

16 Claims. (Cl. 194—10)

This invention relates to improvements in vending machines of the type which are adapted to dispense merchandise in bottled or package form.

5 An important object of the invention is to provide a control device for the vending mechanism which may be set to automatically prevent further operation of the machine after the reserve supply of packages in the machine has 10 become reduced to a predetermined number.

Another object of the invention is to provide in a machine of the character described, means for automatically transferring the bottles from a movable carrier upon which the bottles are 15 supported to a delivery device which directs them through a discharge port formed in a wall of the cabinet which encloses the vending mechanism.

A further object of the invention is to provide 20 an improved self-locking closure means for the discharge port in the cabinet wall which prevents a person from pilfering from the machine by forcing open the closure means and reaching through the discharge port to the packages stored within the cabinet.

25 Other objects and advantages of the invention will be apparent from the following detailed description, taken in connection with the accompanying drawings wherein I have shown the preferred form in which I have thus far contemplated applying the principles of the invention.

30 Referring to the drawings:

Fig. 1 is a front elevational view of the machine;

Fig. 2 is a side elevational view of the machine as viewed from the right hand side of 35 Fig. 1;

Fig. 3 is a vertical sectional view through the machine, the section being taken on line 3—3 of Fig. 2;

40 Fig. 4 is a fragmentary front elevational view of the upper portion of the movable carrier and the drive means therefor;

Fig. 5 is a fragmentary front elevational view of the lower portion of the carrier;

45 Fig. 6 is a top plan view of the carrier and bottle dispensing mechanism;

Fig. 7 is a fragmentary elevational view, partly in section, illustrating the mechanism for removing the bottles from the trays or cradles of the 50 carrier;

Fig. 8 is a fragmentary sectional view illustrating the mechanism for removing the bottles from the carrier and delivering the same from the machine, the section being taken on line 8—8 of Fig. 1 and being on an enlarged scale;

Fig. 9 is a fragmentary elevational view of the automatic switch mechanism which controls the drive motor for the carrier;

Fig. 10 is a detail section through the automatic cut-out switch mechanism taken on line 10—10 of Fig. 9;

Fig. 11 is a fragmentary elevational view, partly in section, illustrating the parts which direct the bottles from the carrier through a discharge chute formed in a wall of the cabinet;

Fig. 12 is a broken transverse vertical section through the refrigerating and storage cabinet, the bottle vending portion of the apparatus being omitted so as to more clearly illustrate the path of air flow in the cabinet; and

Fig. 13 is a wiring diagram of the electrical control circuits which are provided for regulating the operation of the carrier drive motor.

Referring to the drawings in detail, and first particularly to Figs. 1-3, the apparatus is enclosed in a cabinet which in the embodiment shown is rectangular in shape, the front and back walls thereof being indicated by the numerals 15 and 16 (Fig. 12), respectively, and the side walls of said cabinet being indicated by the numerals 17 and 18. The bottom wall of the cabinet, which is indicated at 19, is provided on its lower surface with a rim or strip 21 which extends completely around the bottom wall 19 and serves as a footing to hold the main portion 20 of the cabinet a slight distance from the floor.

The top of the cabinet is closed by a top wall or cover 22 (Fig. 3) which rests on the upper edges of the walls 15, 16, 17 and 18. As will more fully hereinafter appear, the compartment formed by the walls 15, 16, 17 and 18, together with the bottom wall 19 and the top wall 22, serves as a combined storage and refrigerating cabinet for the bottles which are to be dispensed.

The construction of these walls is preferably of the form shown in Fig. 12, each wall consisting of inner and outer sheet metal plates 23 and 24 which are separated by a body of heat insulating material 25 which may consist of cork, compressed fiber, or the like. The side wall 18 is 25 provided with a hinged door 26 and is also provided immediately below the door 26 with a removable panel 27. of a series of trays or cradles 29 which are hung between a pair of endless carrier chains 31 and 32 (Fig. 8). Each of the trays 29 consists of a curved plate 33, which may be made of sheet metal, or the like, and a pair of upwardly projecting arms 34 which are apertured to receive pins 35, the latter being carried by blocks 36 which are fixedly secured to the links of the carrier chains. The curved plates 33 of the trays are shaped to conform to the contour of the bottles 37 resting thereon, and the free pivotal support for the trays provided by arms 34 and pins 35 insures that the tray will always be in position so that the bottle will not roll therefrom.

Continuing the reference to Figs. 3-5, the carrier chains 31 and 32 (Fig. 8) are arranged to efficiently utilize the space which is available for the storage of bottles. To this end said chains 20 are arranged transversely of the cabinet in a series of eight vertical flights, being supported in the cabinet on a heavy frame consisting of an upper pair of cross bars 38 and a lower pair of cross bars 39. The bars 38 and 39 are tied together by vertically disposed tie rods 40 and by transversely disposed tie rods 41. Rods 40 and 41, together with bars 38 and 39, form a rigid frame which may be removed bodily from the cabinet through the opening provided by door 25 26 and panel 27. The upper pair of bars 38 carry three pairs of idler sprockets 42 and one pair of drive sprockets 43. The sprockets 42 are carried on stub shafts 44 which are journaled for free rotation in the frame bars 38. The drive sprockets 43 are fixedly secured to a drive shaft 45 which extends between cross bars 38. The lower pair of cross bars 39 are provided with three pairs of idler sprockets 46, which are journaled in said bars by stub shafts 47. Two additional pairs of idler sprockets 48 are journaled in the bars 39 below, and outside of, the sprockets 46. The carrier chains 31 and 32 take over sprockets 42 and 43 at the top of the cabinet and also take over sprockets 46 and 48 at the bottom of the cabinet, the several sprockets being so positioned 45 that the chains will move downwardly from drive sprockets 43 around the lower sets of sprockets 48 and thence upwardly around the pair of sprockets 42 positioned at the extreme left in Fig. 4, from which point the chains pass alternately up and down between sprockets 42 and 46 back to drive sprockets 43. The path of travel of the carrier chains is clearly indicated by the arrows in Fig. 3. Pairs of small idler sprockets 50 (Fig. 5) are provided to support the lower run of the chains extending between sprockets 48. Power for driving sprockets 43 is supplied by an electric motor 49 which is bolted to a base plate 51, the latter in turn being pivotally connected 50 to a bolt 52 to a frame bracket 53. The armature shaft of motor 49 connects through gears (not shown) contained in a housing 54 with a shaft 55, the forward end of which is journaled in a bearing bracket 56 which projects upwardly from the motor base plate 51. Shaft 55 carries a small sprocket 57 and shaft 45 is provided at its forward end with a large sprocket 58. Sprockets 57 and 58 are connected by a chain 59. A driving connection is thus provided between the armature shaft of motor 49 and shaft 45, it being understood that sprocket wheel 58 is rigid on shaft 45. The tension on driving chain 59 may be adjusted by means of a bolt 61 which is threaded into a tapped opening in the motor base plate 51, the head of said bolt resting on cross bar 38.

The bolt 61 serves to support one side of the motor base plate, and by adjusting the position of the bolt in said base plate the tension on chain 59 may be varied as desired.

Before giving an explanation of the mechanism for controlling the operation of the carrier, I shall briefly describe the novel system of refrigeration which is provided for cooling the bottles in such a way that a dry, cold bottle is always dispensed to the operator. This system of refrigeration may be employed for cooling machines of various types, and forms the subject matter of application Serial No. 55,531 filed by James T. Smith under date of December 21, 1935 (Patent No. 2,160,760, issued May 30, 1939). 15

Referring to Figs. 3 and 12, the general plan of refrigeration involves the circulation of dry cooled air around the bottles while they are supported on the movable carrier, the air being cooled by passing it over an enclosed cooling element. In accordance with this general scheme, there is provided adjacent the rear wall 16 of the cabinet a cooling unit 62 which comprises a comparatively flat liquid-tight receptacle consisting of spaced sheet metal walls 63 (Fig. 8). 20 This receptacle is cooled by passing a refrigerant, such as methyl chloride, through a coil 64 which is connected at one end with the suction side of a compressor 65 (Fig. 3), the other end thereof connecting with a condenser 66. The compressor- 30 condenser unit 65, 66 is mounted on top wall 22 of the cabinet and is enclosed by a sheet metal casing 67 which rests on said top wall 22. This compressor-condenser unit may be of conventional form, the unit shown being driven by an 35 electric motor 68 which has driving connection with the compressor 65 through a belt 69. A fan 71 mounted on the motor shaft blows air through the condenser 66 to effect cooling of the refrigerant. 40

Continuing the reference to Figs. 3 and 12, air is circulated through the cabinet along the path indicated by the arrows in Fig. 12 by a blower 72, which may be of conventional form, the one shown including a rotor 73 having blades 74 projecting therefrom. A sheet metal housing 75 forms a blower compartment which is divided by a partition member 76 into intake and discharge sections which are indicated by the numerals 77 and 78, respectively. The rotor 73 is turned in 45 a clockwise direction, viewing Fig. 3, said rotor being connected by a belt 79 with a pulley 81 which is secured to the crank shaft of the compressor 65. Air driven from the discharge section 78 of the blower 72 passes downwardly over 55 the bottles 37, as indicated by the arrows 82 (Fig. 3). The air which is thus driven by the blower downwardly over the bottles is directed from the bottom of the cabinet to the suction side 77 of the blower by a vertically disposed baffle plate 83, which is mounted in the cabinet parallel to, and adjacent, the back wall 16 and slightly in front of cooling unit 62. 60

It will be noted from Fig. 12 that plate 83 extends downwardly nearly to the bottom of the cabinet, leaving a comparatively narrow passage 84 through which the air is sucked upwardly along a vertical channel 85, in which cooling unit 62 is positioned. Passing upwardly along channel 85 the air moves over the cooled walls 63 and 70 is effectively cooled, the walls 63 of the cooling unit 62 presenting a considerable surface area over which the air must pass. When the air reaches the top of channel 85 it is directed forwardly into a channel 86, whence it passes to the 75

intake section 77 of the blower 72. The channel 86 is formed by a vertically disposed partition wall 87 which joins with a horizontally disposed partition wall 88. In order to prevent transmission of heat to the air as it passes through the blower 72, there is provided around the inner wall 75 thereof a layer of insulating material 89 (Fig. 3), which is enclosed by a sheet metal jacket 91.

One of the important features of this refrigerating system involves the use in the cooling unit 62 of a hold-over fluid which is comparatively easily frozen. Machines of this type are usually used extensively by purchasers during the daytime and are used comparatively little at night. In other words, they are subject to periods of peak demand. In order to effectively meet the cooling requirements for the period of peak demand, a hold-over medium such as water is used, which, during the period of minimum use of the machine, may be frozen to ice. The latent heat of fusion of the ice, which corresponds to the amount of heat which is absorbed from the air in the cabinet to effect melting of the ice, thus provides much greater cooling power than would be provided by an ordinary brine solution, for example, which, during the period of minimum demand, would merely be cooled to a low temperature without actually being reduced to a solid. It will be evident that this refrigerating system will effect dry cooling of the bottles, so that the purchaser always receives a dry cold bottle. Any moisture in the air which condenses on the walls of the cooling unit 62 does not come into contact with the bottles since said unit is positioned at the back of the cabinet and is separated from the bottle compartment by plate 83.

The mechanism for removing a bottle from the carrier and discharging it from the cabinet to the customer will now be described, reference being had particularly to Figs. 4, 7 and 8. The front wall 15 of the cabinet is provided with an opening 92, in which is positioned a downwardly inclined sleeve 93 which is formed of Bakelite or other suitable heat insulating material. The inner end of sleeve 93 registers with an opening 94 formed in a heavy frame plate 95 which is hung from the upper front cross bar 38. Said sleeve 93 is locked in position in the cabinet wall by a pair of rings 96 and 97, which are separated by a gasket 98. A bottle passing from the cabinet through sleeve 93 is received in a cup or receptacle indicated generally by the numeral 99. This receptacle consists of a metal face plate 101, which is secured to the cabinet wall 15, the lower portion of said plate being provided with a forwardly projecting shelf 102 having a pair of spaced rubber covered prongs 103 (Fig. 11) projecting from the upper edge thereof, said prongs being positioned so that they will be struck by the lower end of the bottle as it slides out through opening 92. The face plate 101 is also preferably provided with a conventional cap opening device 104 (Fig. 1).

The bottles are removed from the trays 29 on the carrier and directed through sleeve 93 by a pair of spaced fingers 105 which are carried on a cross bar 106, the latter being connected at its opposite ends by rivets 107 to arms 108, each of said arms 108 being pivoted by shoulder screws 109 to frame brackets 111. In the normal position of the parts, shown by the solid lines in Fig. 7, it will be noted that the fingers 105 extend beyond or overlap shoulders 112 (Fig. 6) which are formed in the bottle supporting trays

29, said shoulders being formed in the trays by cutting away portions of the metal therefrom to provide openings somewhat wider than the fingers 105.

In Fig. 7 three of the trays 29 are shown. It will be apparent that as a tray passes from the position of the uppermost tray of Fig. 7 downwardly around shaft 45 to the position of the intermediate tray in said figure, a bottle resting on the tray will impinge against the ends of 10 downwardly inclined fingers 105, and upon continued downward movement of the carrier, will be rolled from the tray along the fingers 105 onto a curved plate 113, the position of a bottle on said plate 113 being indicated by the 15 dot and dash circle 114 in Fig. 7. The shouldered portions 112 formed in trays 29 are sufficiently deep so that there is no interference between the tray and the ends of fingers 105, the latter merely serving to roll the bottle from the tray 20 as the latter moves downwardly around shaft 45. It will be further noted from Fig. 7 that the fingers 105 and their supporting bar 106 may be swung as a unit upwardly from the solid to the dotted line position of said figure, thereby 25 allowing the bottle carrier to be moved to any desired position without permitting the bottles to be removed as they pass the discharge station. A lever 100, fulcrumed at 120 to the frame, and having pin and slot connection at 130 with one 30 of the arms 108, may be grasped and pulled downwardly to throw fingers 105 and bar 106 to the dotted line position of Fig. 7. In this position of the parts the trays may be reloaded by the proprietor as they move downwardly through the 35 space normally occupied by the fingers 105. Coil springs 115, connected at one end to arms 108 and at the other end to pins 116, yieldingly hold said fingers 105 in either the operative or inoperative position, depending upon where they have 40 been placed by the operator.

The arrangement of the fingers 105 so that they may be thrown to inoperative position, particularly facilitates reloading in cases where it is desired to have a reserve supply of the articles 45 of merchandise on the carrier after the regular supply has been exhausted. For example, as will presently appear, in the vending mechanism constructed in accordance with the present invention, means is provided for preventing further operation of the machine after the supply of bottles on the carrier has been reduced to a certain number, say for instance, twenty bottles. When this occurs the proprietor may throw fingers 105 to inoperative position and then advance the 50 carrier until the twenty bottles have passed the discharge station, whereupon he may proceed to fill the empty trays as the carrier advances to move them across the discharge station. When the last of the trays has been filled the first 55 bottle of the reserve supply will be back to the discharge station and will be the first one dispensed after the machine is restored to operation. Where refrigeration is provided for the cabinet in which the vending mechanism is contained the reserve supply will always be cold and I am thus able to reload in such a way that the first bottles dispensed after reloading will be taken from this cold supply.

Referring particularly to Figs. 7 and 8, the 70 curved plate 113 which receives the bottle from fingers 105 is mounted on spaced brackets 110, which are pivotally supported on a shaft 117, the latter being supported on a plate 118 which is connected by screws 119 to cross bar 38. A coil 75

spring 121, connected at one end to a lip 122 on one of the brackets 110, and at the other end to an adjustable bolt 123 carried by plate 118, tends to pivot said plate 113 in a clockwise direction, viewing Fig. 8, to hold it in the horizontal position shown in Fig. 8, in which position it is adapted to receive a bottle from the fingers 105. The discharge opening 94 formed in plate 95 is normally closed by a fiber gate plate 124. This gate plate is pivotally connected to the forward end of plate 113 by a pair of lugs 125 which are spaced on said plate 124 in position to be received between lugs 126 which project downwardly from the forward ends of brackets 110, said lugs 126 being provided with pins 127 which are received in slots 128 formed in lugs 125. The lower edge of said gate plate 124 is provided with a second pair of lugs 129 which are positioned immediately adjacent a pair of correspondingly spaced plates 131, the latter being secured to plate 95 by bolts 132. The lower pair of lugs 129 are provided with pins 133 which engage in rearwardly inclined slots 134 formed in plates 131. In the position of these parts shown in Fig. 8, gate plate 124 completely closes the discharge opening 94 in plate 95. When, however, a bottle rolls from fingers 105 onto plate 113, the latter pivots downwardly under the weight of the bottle in a counterclockwise direction, viewing Fig. 8, to assume the position shown in Fig. 11, this downward swing of plate 113 under the weight of the bottle being retarded by coil spring 121.

It will be noted from Figs. 8 and 11 that during this downward swing of plate 113 gate plate 124 has been shifted downwardly to open discharge opening 94, thus permitting the bottle on plate 113 to slide therefrom through opening 94 and sleeve 93 onto the receiving receptacle 102. During this movement gate plate 124 follows the rearward swing of plate 113, being guided in its movement by pins 133 which move along guide slots 134. As soon as the bottle slides from plate 113 through the discharge opening spring 121 swings the plate 113, together with gate plate 124, back to the position shown in Fig. 8, in which position the discharge opening 94 is closed.

To prevent a person from forcing gate plate 124 open by reaching through the sleeve 93, I provide notches 135 near the upper ends of slots 134. A person attempting to force gate plate 124 open would push inwardly thereon and also would attempt to force said plate downwardly. When this is attempted the pins 133 slip into notches 135 and are locked by said notches against further downward movement, thus positively preventing movement of said gate plate 124 to the open position.

A description will now be given of the coin controlled mechanism which is provided for operating the carrier drive motor 49 to bring the bottles successively to the discharge station. Referring particularly to the wiring diagram of Fig. 13, a coin introduced into a coin slot 136 (Fig. 1) formed in a coin slot plate 137 which is supported on the front of the cabinet, falls downwardly along a chute 138 which directs it between an arm 139 and one arm 141 of a switch 142, the coin coming to rest between said arm 139, and a fiber strip 143 which is carried on the lower end of arm 141. The other arm of switch 142 is indicated at 144. Switch 142 completes a circuit through carrier drive motor 49, this circuit being traced from a lead 145, which connects with a source of power supply, through a terminal block 146 and a wire 147 which connects with switch

arm 141. From this point the circuit is carried through switch arm 144, and a wire 148, to a terminal block 149 which is connected by a wire 151 to one side of the motor 49, the return from motor 49 being through a wire 152 to a terminal block 153, the latter being connected by a lead 154 to the other side of the power supply. As long as a coin is held in the position of the coin 155 (Fig. 13) switch 142 remains closed and motor 49 operates to advance the bottle carrier. The coin 10 is released from this position to stop the carrier by the closing of a circuit through the coil of an electromagnet 156 which is supported on a shelf 157. The vertically disposed arm 139 which engages the coin 155 is joined to a horizontally 15 disposed arm 158 which is pivotally supported at 159 to shelf 157. The arm 158 constitutes the armature of electromagnet 156, so that when the latter becomes energized said arm 158 is pulled downwardly with the result that arm 139 is moved 20 to the left, viewing Fig. 13, a distance sufficient to release coin 155 from switch arm 141. The energizing circuit for electromagnet 156 is controlled by a mercury switch which is indicated generally by the numeral 161. The mechanical parts 25 which operate this switch will be presently described in detail. The switch itself consists of a sealed mercury-containing tube 162, one terminal of which is connected to lead line 154 through a wire 163 and terminal block 153. The circuit to 30 the other terminal of said switch 161 is traced from lead line 145 through terminal block 146 and wire 147 to a wire 164 which connects with one end of the coil of electromagnet 156, the other end of said coil connecting with a wire 165 which leads to a terminal block 166, the latter being connected to switch 161 through a wire 167. So long as switch 161 is in the inclined position shown in Fig. 13, the energizing circuit for electromagnet 156 remains open and arm 139 remains 35 40 in coin retaining position. However, when switch 161 is tilted to horizontal position by a mechanism presently to be described, a circuit is closed through electromagnet 156 and arm 158 is pulled downwardly to effect release of the coin 45 155, thereby opening the circuit through motor 49 and stopping movement of the carrier.

Continuing the reference to Fig. 13, the free end of arm 158 is provided with a laterally projecting pin 168 which extends into coin chute 50 138. So long as electromagnet 156 remains de-energized, as shown in Fig. 13, arm 158 is so positioned that pin 168 will direct a coin along chute 138 into circuit closing position between arm 139 and switch arm 141. When, however, 55 electromagnet 156 is energized pin 168 is moved downwardly to the dotted line position indicated by the numeral 169. In this position said pin will prevent a coin from passing downwardly in chute 138 to circuit closing position between arm 60 139 and switch arm 141, such a coin being deflected laterally in chute 138 along a branch chute 171 which returns the coin to an exposed receptacle 172 (Fig. 1) formed in coin slot plate 137, from which it may be removed by the 65 operator. So long as electromagnet 156 is energized it thus becomes impossible for the operator to effect movement of the carrier, a coin introduced into the coin slot during this interval being returned to the operator without effecting closing 70 of the circuit of carrier drive motor 49. The purpose of this is to prevent movement of the carrier to effect release of a bottle therefrom until the previously dispensed bottle has had an opportunity to pass through the discharge opening in 75

- the cabinet and, as will presently appear, mechanism is provided for holding switch 161 in the closed circuit position until a bottle delivery has been completed.
- 5 An auxiliary mercury controlled switch 173 is provided for energizing electromagnet 156 independently of the switch 161. This switch, which is adapted to be closed after a prescribed number of bottles have been dispensed from the machine, 10 as will more fully hereinafter appear, is connected in circuit with the wire 165, which leads from the electromagnet 156, through terminal block 166 and a wire 174. The return from switch 173 is through a wire 175 and a wire 176, the latter 15 connecting with wire 163 which leads to terminal block 153 and lead line 154. This circuit through switch 173 and electromagnet 156 is independent of the circuit through switch 161 and electromagnet 156, so that the latter may be energized by 20 either one of these switches, even though the other one may be open.
- A pilot light 177 is mounted on the front of the cabinet immediately behind a glass covered opening 178 (Fig. 1) formed in coin slot plate 25 131. The circuit for this light is arranged to be energized when the last bottle which may be obtained from the machine has been dispensed. This circuit is controlled by a mercury switch 179 which, as will presently appear, is closed 30 simultaneously with the closing of switch 173. The circuit through pilot light 177 is traced from lead wire 145 through terminal block 146, and wire 147, to a wire 181, the return from the light being through a wire 182, a terminal block 183, 35 and a wire 184 to one side of switch 179. The other side of this switch connects through a wire 185 with wire 176, the latter, in turn, connecting through wire 163 and terminal block 153 with lead line 154.
- 40 A description will now be given of the mechanism which operates the mercury switches 161, 173 and 179, reference being had to Figs. 7, 8 and 9. The tube 162 of switch 161 is mounted in a clip 186 which is secured to a plate 187, the 45 latter being pivoted at 188 to a frame bracket 189. The lower edge of plate 187 is provided with a notch 191. A pin 192 carried by bracket 189 extends into said notch to limit the tilting movement of plate 187 and switch 161, the latter being 50 overbalanced on pivot 188 so that it normally remains in the open circuit position as shown in Fig. 9. Two separate mechanisms are provided for tilting plate 187 to close switch 161. The first of these comprises: a yoke, consisting of a pair 55 of arms 193 and 194, which are pivoted to bracket 189 by a sleeve 195, through which extends a bolt 196, the lower ends of said arms being connected by a metal strip 197; and a vertically disposed link 198, the upper end of which is 60 pivotally connected by a pin 199 to plate 187, the lower end of said link being pivotally connected at 201 to an arm 202 which forms an integral part of arm 194.
- It will be noted from Fig. 7 that strip 197 on 65 the lower ends of arm 193, 194 is positioned in the path of a bottle rolling downwardly along fingers 105 to plate 113. The open circuit position of the parts is indicated by the solid lines in Fig. 7, a coil spring 203, connected at one end to arm 194, and at the other end to a lug 204 on the frame, serving to urge said arms in a clockwise direction, viewing Fig. 7. A cam lug 205 formed on the upper end of arm 194 engages a cross rod 206 on the frame to limit the movement of arms 70 193, 194 under the action of spring 203. A bottle
- rolling downwardly along fingers 105 will strike against strip 197 to move said strip and the arms 193, 194 from the solid to the dotted line position shown in Fig. 7. In pivoting to this position arm 194 raises link 198 which, in turn, tilts plate 187 5 a slight distance in a counterclockwise direction, viewing Fig. 9, to effect closing of switch 161. The closing of this switch, as previously explained, energizes electromagnet 156 to release the coin, thereby deenergizing the carrier drive 10 motor 49. As long as this switch remains closed the operator cannot restart the motor by putting a coin in the coin chute, such coin being returned through branch chute 171 (Fig. 13).
- The above described mechanism for closing 15 switch 161 is effective to hold the switch in closed position only during a portion of the interval in which the bottle remains on plate 113. It will be apparent from Fig. 11 that as the bottle slides from the dotted to the solid line position in said 20 figure, it will move clear of strip 197 at about the time when the bottle is half way through the discharge opening in the plate 95. As soon as the bottle clears strip 197 spring 203 would normally act to return switch 161 to open circuit 25 position. To prevent the opening of the switch at this time, and to insure that the same will be held closed until the bottle has cleared the discharge opening 94 in plate 95, and until gate plate 124 has returned to the closed position of 30 Fig. 8, I provide mechanism for holding link 198 and plate 187 in switch closing position until the bottle has entirely cleared plate 113. In the embodiment shown this mechanism consists of a link 207, the lower end of which is pivoted at 208 35 to one of the brackets 110, the upper end of said link being slotted to receive a pin 209 which is carried by a lever 211, the latter being fulcrumed on frame plate 189 by a pin 212. An arm 213 of lever 211 extends through a slot 214 (Fig. 7) 40 formed in link 198. In moving from the solid to the dotted line position in Fig. 7, the arms 193 and 194 raise the link 198 to effect closing of switch 161 and during this movement lever 211 is pivoted in a clockwise direction, viewing Fig. 10. 45 This, however, has no effect on link 207 by reason of the pin and slot connection formed between the upper end of said link and lever 211. Switch 161 may thus be closed by arms 193, 194 independently of lever 207. When, however, plate 50 113 swings downwardly under the weight of a bottle link 207 is lowered and when the slot in the upper end thereof engages pin 209, said link holds lever 211 in the position shown in Fig. 11, in which position switch 161 is closed. Link 207 and 55 lever 211 thus serve to maintain switch 161 closed until a bottle has cleared plate 113 so that the latter is free to be raised to position for receiving the next bottle. The dual control for switch 161 thus insures that the carrier drive motor will 60 remain deenergized until a bottle has actually passed through the discharge opening 94 in plate 95. Jamming of the bottles is thus positively prevented, inasmuch as the operator must wait until one bottle is delivered before he can operate the 65 carrier to effect a second delivery.
- The mechanism for operating the shut off switch 173 and the pilot light switch 179 will now 70 be described, reference being had to Figs. 9, 10 and 11. These switches are secured by clips 215 to a rocker plate 216, the opposite sides of which are bent downwardly to provide brackets 217 and 218, said brackets being apertured to receive a shaft 219 which is carried by the upper end of a frame post 221, the latter including a laterally 75

projecting frame arm 222 which connects with the frame plate 189. Bracket 217 is notched as indicated at 223, said notched portion engaging a pin 224 carried by post 221 to limit the tilting of plate 216 on shaft 219. A coil spring 226 extending between shaft 219 and a pin 226 projecting downwardly from plate 216 urges the latter in a clockwise direction, viewing Fig. 9, to hold one edge of the notched portion 223 against pin 224, this position of the parts, which corresponds to the open circuit position of switches 173 and 179, being shown in Fig. 9. The inner bracket 217 is provided with an extension 227 which carries a laterally projecting lug 228. A short shaft 229 is journaled for free turning in a bearing 231 (Fig. 10) which is formed in post 221. An arm 232 is fixedly secured to shaft 229, said arm being of such length that when turned to vertical position it will strike the outwardly projecting lug 228 carried by the rocker plate extension 227. The arm 232 and shaft 229 are urged in a counterclockwise direction, viewing Fig. 10, by a heavy coil spring 233, one end of which is connected by a screw 234 to arm 232, the other end of said spring being fixed to bearing 231 on the frame. The end of shaft 229 which projects outwardly from post 221 carries a pawl arm 235 which rotates freely on an enlarged portion 236 of the shaft. A ratchet wheel 237 is mounted for free rotation on the shaft immediately adjacent pawl arm 235, and a dial 238 is positioned on the shaft immediately adjacent ratchet 237. A pointer 239 is provided at its center with a squared opening which fits over a squared portion 240 on shaft 229. The outer end of shaft 229 is threaded to receive a locking cap 241. When this cap is screwed into position it firmly clamps ratchet 237, dial 238 and pointer 239 against the shoulder provided by the enlarged portion 236 of shaft 229, these parts being thus clamped together to turn as a unit with shaft 229, but leaving the pawl arm 235 free to turn independently of said shaft.

Pointer 239, which is fixed on shaft 229, is diametrically disposed with respect to arm 232, this being clearly shown in Fig. 9. In the embodiment shown the dial 238 is divided into ninety-five divisions which correspond to the capacity of the bottle carrier, these divisions being numbered by fives, as clearly shown in Fig. 9. As previously stated, dial 238 and arm 232 are both fixed to shaft 229 and are diametrically disposed with respect to one another. Dial 238 carries a stop plate 242 (Fig. 8) which is provided with a projecting lug 243 which is located slightly to the left of the mark "95" on dial 238. In the position of the parts shown in Figs. 8 and 9, pointer 239 is set opposite the number 20 on dial 238, in which position of said pointer arm 232 is disposed seventy-five spaces in a counterclockwise direction from the position in which it will strike against lug 228 to tilt plate 216 to circuit closing position. Therefore, with the pointer 239 set opposite the numeral 20, seventy-five step movements of ratchet wheel 237 and dial 238 in a clockwise direction, viewing Fig. 9, would be required to bring arm 232 into contact with lug 228 to close the circuits through switches 173 and 179. With the carrier loaded to its full capacity of ninety-five bottles, and with pointer 239 set in this position, it will be apparent that after seventy-five bottles have been dispensed, switch 173 will be closed, thereby energizing the coil of solenoid 156 to release the coin from circuit closing position against switch 142 and deenergizing motor 49. At this same time switch 179 is also

closed to turn on the pilot light 171. Under these conditions twenty bottles will remain in the carrier, these bottles constituting a hold-over supply. This is one of the important features of the invention. A number of bottles may be retained in the machine after a given number have been dispensed, so that after the machine has been refilled and restored to operation the first bottle which will be dispensed will be one taken from the hold-over supply and will, therefore, always be cold. Of course, if it were desired to dispense the entire supply it would merely be necessary to set pointer 239 opposite the "95" mark on dial 238, in which case arm 232 would not strike lug 228 to deenergize the motor until the entire supply of bottles had been dispensed. The setting of pointer 239 is accomplished by merely loosening the locking cap 241 which frees the dial 238 and ratchet wheel 237 from shaft 229. With these parts thus released pointer 239 may be set opposite the desired number on dial 238, it being understood, of course, that during this operation dial 238 is held in the position shown in Fig. 8, in which tooth 243 thereon rests against a stop pin 244, said stop pin projecting from a plate 245 which is supported from frame post 221. Plate 245 also carries an index plate 246 (Fig. 8) having an arrow 247 thereon which points toward dial 238 to indicate to the operator the position of the dial. By subtracting the number opposite pointer 239 from the number opposite the fixed pointer 247, the proprietor can tell exactly the number of bottles which may be dispensed before the circuit for the carrier drive motor will be opened to prevent further operation of the machine.

Dial 238, ratchet wheel 237 and arm 232 are advanced one step toward circuit breaking position for the motor 49 each time a bottle is dispensed from the machine. As will be noted from Figs. 8, 9 and 11, the free end of pawl arm 235 is provided with an adjustable screw 248 which is positioned in the path of movement of lug 122 on the bottle supporting bracket 110. When bracket 110 is pivoted under the weight of a bottle from the position shown in Fig. 8 to the position shown in Fig. 11, lug 122 strikes screw 248 on the end of ratchet arm 235, moving the latter a slight distance in a clockwise direction, viewing Fig. 9. Pawl arm 235 carries a pawl 249 which is held by a coil spring 251 against the teeth of ratchet wheel 237. Each time that bracket 110 tilts downwardly to carry lug 122 against screw 248, ratchet wheel 237 is turned by pawl 249 one step in a clockwise direction, viewing Fig. 9, to carry dial 238 and arm 232 one step or space toward circuit breaking position. There is thus a regular step-by-step movement of arm 232 toward circuit breaking position, which movements are timed with the bottle vending operations so that after the allowed number of bottles have been dispensed the end of arm 232 will move against lug 228 to close switch 173 and open the motor circuit.

As shown in Fig. 9, dial 238 may be turned to zero position when it is desired to refill the machine by means of a lever 252 which is fulcrumed at 253 to plate 245. A coil spring 254 extending between one end of lever 252 and plate 245 holds said lever 252 in the substantially horizontal position shown in Fig. 9. A pawl 255 carried by plate 245 engages the teeth of ratchet wheel 237, being yieldingly held in contact therewith by a coil spring 256 which extends between plate 245 and a pin 257 on said pawl which pro-

jects through a slot 258 formed in plate 245. This pawl prevents a counterclockwise turning of ratchet wheel 237 and dial 238 under the action of spring 233. If the proprietor desires to reset dial 238 to zero position, he merely pushes downwardly on an arm 259 which is carried on one end of lever 252. A downwardly projecting portion 261 on lever 252 is thus moved against pin 257 and withdraws pawl 255 from the teeth 10 of ratchet wheel 237, allowing the latter, together with dial 238, to be returned to zero position under the action of spring 233. Pawl 249 is removed from ratchet wheel 237 at this time by engagement of lever 252 with a pin 250 which projects 15 inwardly from said pawl.

The operation may be summarized as follows: The proprietor first loads the carrier by opening door 26 and pulling downwardly on lever 100 to throw arms 105 to the dotted line position shown 20 in Fig. 7. The circuit through motor 49 is then closed by closing a manually operable switch 262 (Fig. 11) which shunts the coin-controlled switch 142. The carrier will then be moved continuously in the direction of the vertical arrows shown in 25 Fig. 3 and the bottles may be loaded on the trays 29 as they move downwardly past the discharge station opposite the swinging plate 113. After the carrier has been fully loaded switch 262 is opened to shut off the carrier drive motor and lever 100 is raised to throw fingers 105 back to the position shown by the solid lines shown in 30 Fig. 7. Pointer 239 (Fig. 8) is then set opposite the number on dial 238 corresponding to the 35 number of bottles which it is desired to retain in the machine as a hold-over supply. The machine is then locked and ready for use. A coin introduced through coin slot 136 (Fig. 1) closes switch 142 which energizes the carrier drive motor 49 and starts movement of the carrier to 40 bring a bottle on one of the trays 29 (Fig. 8) opposite the discharge station where it is engaged by fingers 105 and rolls downwardly onto the swinging plate 113. In moving onto this plate the bottle strikes arm 197, swinging the latter from the solid to the dotted line position shown 45 in Fig. 7, which operation raises link 198 and tilts mercury switch 161 (Fig. 8) to circuit closing position. The closing of this switch energizes electromagnet 156 to open the circuit for the 50 carrier drive motor 49 and at the same time pin 168 (Fig. 13) is moved into position to block the portion of coin chute 138 which directs a coin to switch 142. As plate 113 swings downwardly under the weight of a bottle from the position 55 shown in Fig. 8 to the position shown in Fig. 11, link 201 is pulled downwardly to hold switch 161 in closed circuit position, said switch thus remaining closed to prevent a succeeding energization of the carrier drive motor from the time the 60 bottle strikes arm 197 until the time it slides from plate 113 through the discharge opening 92. As said plate 113 swings downwardly it also carries gate plate 124 from the closed position shown in Fig. 8 to the open position shown in Fig. 11 to 65 allow the bottle to slide through sleeve 93 to the shelf 102 from which it may be removed by the customer. As soon as the bottle has cleared plate 113 the latter is returned by spring 121 to the normal position shown in Fig. 8, thus allowing switch 161 to fall back to open circuit position, which, in turn, deenergizes electromagnet 156 and opens the coin chute to permit a coin to be directed downwardly along chute 138 to 70 switch 142. Each time that plate 113 swings downwardly to deliver a bottle, lug 122 actuates 75

pawl arm 235 to turn dial 238 and arm 232 one step in a clockwise direction, viewing Fig. 9.

The above cycle of operations is repeated each time a coin is introduced into the machine, the operator receiving a dry, cold bottle for each 5 coin inserted. When the seventy-fifth bottle is dispensed, arm 232 (Fig. 9) will be moved against lug 228 which is carried by the tilting plate 216. When this occurs the mercury switch 173 is tilted to closed circuit position and energizes electromagnet 156 to open the circuit through the carrier drive motor. Switch 173 remains closed so long as arm 232 rests against lug 228 and electromagnet 156 thus remains energized to hold pin 168 in coin obstructing position in the coin chute 15 138. It is thus impossible for the operator to close the switch for the carrier drive motor by inserting a coin, and further operation of the machine is prevented until it is restored to operating condition by the proprietor. The mercury switch 179 (Fig. 9) is closed simultaneously with the closing of switch 173 to energize pilot light 177 (Fig. 9) which lights up the opening 178 (Fig. 1) in the front of the machine and gives the proprietor, as well as the customer, a warning that the machine can no longer be operated to obtain a bottle. At this time twenty bottles will still remain on the carrier, these bottles constituting a reserve supply so that on the first operation, after the carrier has been reloaded, 30 the customer will receive one of the cold bottles taken from this hold-over supply.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. In a refrigerated vending machine, an insulated cabinet, vending mechanism supported in said cabinet, said mechanism including means for supporting a plurality of the articles to be vended and means for dispensing said articles individually from the supporting means through a discharge port in the cabinet wall, and means operated by said dispensing means for preventing further operation of the vending mechanism after the number of articles in the machine have 50 been reduced to a predetermined number but while a substantial number of articles remain in the machine, said vending mechanism including a drive motor and said last-mentioned means comprising a control member adapted to be set 55 before operation of the machine is begun and to be advanced toward effective position by successive vending operations and electrical means including a switch adapted to be actuated by said control member upon reduction of the number 60 of articles in the machine to said predetermined number to prevent further energizing of the drive motor until said control member has been reset, as upon reloading of the machine.

2. In a vending machine, a cabinet, a carrier mounted in said cabinet and provided with means for supporting a series of the articles to be vended, means for moving the carrier to successively present said articles to a discharge port in the cabinet wall, coin-controlled means for starting 70 operation of said carrier moving means, means for transferring the articles from the carrier to said discharge port, means for stopping the carrier upon removal of an article therefrom, and means operated by said transferring means for 75

preventing further operation of the carrier by said coin-controlled means after a predetermined number of articles have been dispensed.

3. In a vending machine, a cabinet, a carrier mounted in said cabinet and provided with means for supporting a series of the articles to be vended, a motor for moving the carrier to successively present said articles to a discharge port in the cabinet wall, coin-controlled means for energizing said motor to start movement of the carrier, means for transferring the articles from the carrier to said discharge port, means for deenergizing the motor to stop the carrier upon removal of an article therefrom, and means operated by said article transferring means for preventing reenergization of the motor by said coin-controlled means after the number of articles in the machine have been reduced to a predetermined number but while a substantial number of articles remain in the machine.

4. In a refrigerated vending machine, the combination of an insulated cabinet, a carrier provided with means for supporting a series of the articles to be vended, coin-controlled electrically-operated means for moving the carrier to successively present said articles to a discharge station, means for dispensing the articles when presented at said station, means for stopping the carrier after an article has been presented to the discharge station, and mechanism for preventing further operation of said coin-controlled means to operate said carrier after the number of articles in the machine have been reduced to a predetermined number but while a substantial number of articles remain in the machine, said mechanism comprising electrical means including a switch adapted to be actuated through action of said dispensing means when the number of articles in the machine is reduced to said predetermined number to prevent further operation of said carrier-moving means until the mechanism has been reset, as upon reloading, said mechanism also including a control member which may be set in various positions to change the point at which said mechanism will be operated.

5. A machine for vending merchandise in bottled or package form comprising, in combination, a carrier provided with a plurality of holders arranged to support the bottles in spaced relation on the carrier, a motor for moving said carrier to successively present said holders to a discharge station, coin-controlled means for energizing said motor to start movement of the carrier, means for deenergizing said motor to stop the carrier after a bottle has been presented to the discharge station, and stop mechanism for preventing further energization of the motor by said coin-controlled means after the number of articles in the machine have been reduced to a predetermined number but while a substantial number of articles remain in the machine, said mechanism including a control member which may be set at various positions to change the number of bottles which may be dispensed before further operation of the carrier is prevented.

6. In a vending machine, a cabinet, a carrier mounted in said cabinet and provided with means for supporting a series of the articles to be vended, means for moving the carrier to successively present said articles to a discharge port in the cabinet wall, coin-controlled means for starting operation of said carrier moving means, means for transferring the articles from the carrier to said discharge port, means operated by said article transferring means for stopping the carrier

upon removal of an article therefrom, and additional means operated by said transferring means for preventing further operation of the carrier by said coin-controlled means after the number of articles in the machine have been reduced to a predetermined number but while a substantial number of articles remain in the machine.

7. In a vending machine, a cabinet, a carrier mounted in said cabinet, a motor for moving said carrier to successively present a series of articles supported thereon to a discharge port in the cabinet wall, coin-controlled means for energizing said motor to start movement of the carrier, means for transferring the articles from the carrier to said discharge port, and stop mechanism for preventing closing of the motor circuit by said coin-controlled means after a predetermined number of articles have been dispensed, said mechanism including a circuit breaking device, a rotatable element having a member thereon for engaging said device to open the motor circuit, said element being adjustable to permit setting of said member a predetermined distance away from circuit breaking position, and means operated by said article transferring means for returning said element by step movements toward circuit breaking position.

8. In a vending machine, a cabinet, a carrier mounted in said cabinet and provided with means for supporting a series of the articles to be vended, means for moving said carrier to successively present said articles to a discharge port in the cabinet wall, and means for transferring the articles from the carrier to said discharge port comprising a downwardly inclined bar positioned to engage and remove an article from its support on the carrier as the article is moved downwardly against the upper end of said bar, and a pivoted trough member positioned to receive an article moving along said bar and to swing downwardly under the weight of the article to a position in which the article will slide therefrom into the discharge port in the cabinet wall.

9. In a vending machine, a cabinet, a carrier mounted in said cabinet and provided with means for supporting a series of the articles to be vended, coin-controlled means for moving said carrier to successively present said articles to a discharge port in the cabinet wall, a downwardly inclined bar positioned to engage and remove an article from its support on the carrier as the article is moved downwardly against the upper end of said bar, a trough member positioned to receive an article moving downwardly along said bar and to swing downwardly under the weight of the article to a position in which the article will slide therefrom into the discharge port in the cabinet wall, means actuated by an article passing along said bar for stopping the carrier, and means operated by said trough member for holding said stopping means in position to prevent restarting of the carrier by said coin-controlled means until the article has been transferred into the discharge port in the cabinet wall.

10. In a vending machine, a cabinet, a carrier mounted in said cabinet and provided with means for supporting a series of the articles to be vended, a motor for moving said carrier to successively present said articles to a discharge port in a wall of the cabinet, coin-controlled means for energizing said motor to start movement of the carrier, a downwardly inclined bar positioned to engage and remove an article from its sup-

- port on the carrier as the article is moved downwardly against the upper end of said bar, a pivoted trough member positioned to receive an article moving downwardly along said bar and to swing downwardly under the weight of the article to a position in which the article will slide therefrom into the discharge port in the cabinet wall, a circuit breaking device adapted to be actuated by an article passing along said bar to deenergize the carrier drive motor, and means operated by said trough member for holding said device in circuit breaking position to prevent re-starting of the carrier drive motor by said coin-controlled means until the article has been transferred into the discharge port in the cabinet wall.
11. In a vending machine, a cabinet, vending mechanism supported in said cabinet, said mechanism including means for supporting a plurality of the articles to be vended and means for dispensing the articles individually from said supporting means through a discharge port in the cabinet wall, a gate plate normally positioned to close said discharge port, said plate being adapted to be moved by the dispensing mechanism to open position when an article is directed to the discharge port, and means whereby pressure applied externally to said plate will lock the same against opening and thus prevent pilfering from the machine, said means including a device rendered effective by such pressure for resisting opening movement of said gate in the plane thereof as well as for resisting any substantial movement transversely of said plane.
12. In a vending machine, a cabinet, a carrier mounted in said cabinet and provided with means for supporting a plurality of the articles to be vended, means for moving said carrier to successively present said articles to a discharge port in the cabinet wall, means for transferring the articles from the carrier to said discharge port including a trough member pivotally supported adjacent the carrier in position to receive an article therefrom and to swing downwardly under the weight of the article to a position in which the article will slide therefrom into the discharge port in the cabinet wall, a gate plate normally positioned to close said discharge port, said plate being adapted to be moved by said trough member to open position when the latter moves into position for directing the article into said discharge port, and means for locking said gate plate over the discharge port when pressure is applied externally to said plate in an attempt to force it to open position.
13. In a vending machine, a cabinet, a carrier mounted in said cabinet and provided with means for supporting a plurality of articles to be vended, means for moving said carrier to successively present said articles to a discharge port in the cabinet wall, means for transferring the articles from the carrier to said discharge port including a member movably mounted adjacent the carrier in position to receive an article therefrom and adapted to move downwardly under the weight of the article to a position in which the article will slide therefrom into the discharge port in the cabinet wall, and a gate normally positioned to close said discharge port, said gate being adapted to be moved by said member to open position when the latter moves into position for directing the article into said discharge port.
14. In a bottle vending machine, an insulated cabinet having a downwardly and outwardly inclined discharge port in one of its vertical walls, an endless carrier in said cabinet, including means to support a plurality of bottles with their longitudinal axes horizontal and transverse to said carrier, and adapted to successively present said bottles to a position adjacent and above said port, and means for transferring said bottles to said port, comprising a trough pivoted on an axis transverse to its longitudinal axis and positioned normally in a substantially horizontal position substantially parallel to the axes of said bottles with one end above said port, said trough being adapted to swing downwardly under the weight of a bottle to an inclined position aligned with said port, and means for causing a bottle to move in a direction transverse to its longitudinal axis from the carrier to said trough.
15. In a bottle vending machine, a cabinet having a discharge port in a vertical wall, an endless carrier in said cabinet, a horizontal shaft over which a reach of said carrier travels downwardly, said carrier including means to support a plurality of bottles in position parallel to said shaft, and means for transferring said bottles to said port, comprising a trough pivoted on an axis transverse to its longitudinal axis and disposed normally in a substantially horizontal position with one end above said port, said trough being adapted to swing downwardly under the weight of a bottle to an inclined position aligned with said port, a bottle being adapted after passing over said shaft to move in a direction transverse to its longitudinal axis, from the carrier into said trough.
16. In a vending machine, a cabinet, a carrier mounted in said cabinet and provided with means for supporting a series of the articles to be vended, means for moving the carrier to successively present said articles to a discharge port in the cabinet wall, coin-controlled means for starting operation of said carrier moving means, means for transferring the articles from the carrier to said discharge port, means for stopping the carrier upon removal of an article therefrom, and means operable through the action of the articles as they are being dispensed from the machine for preventing further operation of said coin-controlled means to operate said carrier after a predetermined number of articles have been dispensed.

BERT E. MILLS.
